UNITED STATES PATENT OFFICE.

WINIFRED GUGLIELMI (MRS. RUDOLPH VALENTINO), PROFESSIONALLY KNOWN AS NATACHA RAMBOVA, OF NEW YORK, N. Y., ASSIGNOR TO COSMIC ARTS, INC., OF NEW YORK, N. Y., A CORPORATION OF DELAWARE.

COMBINED COVERLET AND DOLL.

Application filed March 6, 1924. Serial No. 697,224.

To all whom it may concern:

Be it known that I, WINIFRED GUGLIELMI (Mrs. RUDOLPH VALENTINO), professionally known as NATACHA RAMBOVA, a citizen 5 of the United States, residing at New York, county of New York, and State of New York, have invented certain new and useful Improvements in Combined Coverlets and Dolls, of which the following is a specification.

This invention relates to an article of manufacture for children's use, and has for its main object to provide an article of the character described which may be converted into 15 a wrap, a carriage robe, or serve as a doll.

With the foregoing and other objects in view, hereinafter stated, the invention consists of the novel construction, combination and arrangements of parts hereinafter more 20 specifically stated, and illustrated in the accompanying drawings, wherein is shown an article embodying the invention in its preferred form, but it is to be understood that changes, variations and modifications may 25 be resorted to without departing from the scope of the invention.

In describing the invention in detail reference is had to the accompanying drawings, which form a part of this specification, and 30 wherein like characters of reference indicate corresponding parts and wherein

Fig. 1 is a front elevation of an article embodying the invention folded so as to be used as a doll or ornamental pillow and

Fig. 2 is a plan of the body of the article extended its full length.

As illustrated, in the drawing 1 represents a body formed of woven or knit material and adapted to be folded over onto itself 40 to form panels or sections, each panel or section preferably having a curved margin 2.

A representation of a doll is attached to one side of the body and is preferably arranged in one of the sections thereof.

The doll section is provided with a face 3 which is secured to the body by means of a row of stitching 4, and the face is preferably built out or raised from the body by means of a backing or filling between the 45 body and face to give the face a more realistic effect than if arranged flat on the body.

A hood 5 is secured to the body with its margins stitched thereto and the hood is

likewise preferably raised somewhat from the body at the portions intermediate its 55 edges by means of backing or filling.

The doll section is also provided with a dress 6 which is preferably free from the body except at its upper and lateral margins which are secured to the body by means 60 of rows of stitching 7. Feet 8 are provided with extensions or legs which are secured to the body and the feet themselves extend below the lower free end of the dress 6 as 65 shown in the drawing.

The feet are free from the body portion and may be moved to a limited extent and may be made of any suitable material such as rubber or cloth stuffed with any suitable material to give a full effect to the feet.

Hands 9 are also provided with extensions connected with the body and extend through slots 10 formed in the dress 6.

The hands like the feet are preferably 75 made of rubber and rounded to give a full effect and appearance and like the feet may be moved to a limited extent relative to the body.

If desired sections representing an under 80 garment may be attached to the body at its lateral and upper margin by rows of stitching.

In the drawing the representation of the doll is shown as placed upon one of the outer 85 sections of the body. That is not an essential feature of the invention and if desired the doll section may be attached to any other section.

It is well understood that children, especially babies must be kept warm and comfortable at all times and during suitable seasons of the year suitable coverings and wraps must be provided in addition to their ordinary dress.

The article herein described and illustrated is specially adapted to be wound around a baby in folds and the folds secured together and around the baby by means of a ribbon 11 or other suitable means which is shown as attached to the body of the article and passed through slits 12 formed in the body of the garment as shown in Figure 2.

The body may be made of any desired width so as to extend beyond the head and feet of a child to the desired extent.

In addition to serving as a wrap or

blanket in folds for a child the body of the article may be extended or folded to a lesser extent and be used as a carriage blanket or robe.

- 5 In both of such cases, that is, whether used as a wrapping blanket, or as a carriage robe, the representation of the doll is displayed and lends a pleasing and ornamental effect to the blanket or robe.
- 10 It is well recognized that babies naturally reach and stretch out their arms and hands and grasp small objects within reach. For that reason, and in order to provide objects to attract the attention of a child the hands and feet are provided and given a free movement to a limited extent in order that they may be grasped and played with by a child as well as to give a realistic effect to the appearance of the doll.
- 15
- 20 In addition to the foregoing uses and purposes when the body is folded on itself and the folds secured together by means of the ribbon 11 the article can be used and fondled by children as a doll. To them the entire
- 25 article is a doll. When so folded moreover the article may be used as an ornamental pillow for a couch or lounge or placed in such a position as a matter of convenience for the parents when not in actual use
- 30 around or over a child.

What I claim as new and desire to secure by Letters Patent is:

1. A convertible robe and doll comprising a fabric body of greater length than width, and a doll formed on said body and extending transversely thereof having a face and a hood raised from said fabric and stitched thereto at its margins, and hands and feet flexibly connected with said fabric body. 35
2. A convertible robe and doll comprising a fabric body of greater length than width, and a doll formed on said body and extending transversely thereof having a head raised from said body and stitched thereto, and feet flexibly connected with said fabric body. 40
3. A convertible robe and coverlet comprising a fabric body of greater length than width, and the simulation of an animate object formed on said body, portions of said object being puffed and stitched at their margins to said fabric and other portions of said object being puffed and flexibly connected with said fabric. 45

In testimony whereof I have affixed my 55 signature.

WINIFRED GUGLIELMI,
(*Mrs. Rudolph Valentino*) pro-
fessionally known as *Natacha*
Rambova.
